GUSTAVE EMILE CHÉDRU, OF NEAUPHLE LE CHATEAU, FRANCE

INTERNAL-COMBUSTION ENGINE

Application filed July 16, 1928, Serial No. 293,132, and in Belgium July 18, 1927.

The present invention relates to specially formed explosion chambers for internal combustion engines.

One of the objects of the invention is to form the piston and cylinder head so that the explosion chamber limited by these elements favors a more efficient explosion wave than is obtained in motors as now constructed.

10 Further objects will appear in the course of the detailed description now to be given with reference to the accompanying drawing, in which the single figure represents a section passing through the spark-plug of a 15 single cylinder of a 2-cycle engine.

Referring to the drawing, *a* is the internal surface of a cylinder head comprising a cooling chamber *b*, an external wall *f*, and a spark-plug opening *d*. Surface *a* is formed 20 so that the greater portion thereof is hemi-spherical. *e* is a water-cooled cylinder block carrying a piston *h* whose head portion includes a partially hemi-spherical surface *j*, and a curved surface *l* intersecting surface *j* at *i* and formed so as to come very close to wall *a* when the piston is at the end of its course.

The curved surface *l* is a sharply sloping ridge which, as is usual in such structures, is 30 located adjacent to, but is spaced slightly from, the inlet side of the cylinder, so as to direct the incoming fuel upward into the combustion chamber and to sweep out the burnt gases into the exhaust. The surface *j* slopes gently towards the exhaust side of the cylinder, and is offset from the center of the piston towards the exhaust side by reason of the presence of ridge *l* which occupies a part 35 of the inlet half of the piston surface. The 40 chamber formed by walls *a* and *j* is thus offset towards the exhaust side, although its width is greater than half the width of the cylinder and one of its edges therefore lies in the inlet half of the cylinder. It will be 45 noted that the open end of wall *a* is out of line with the bore in cylinder-block *e*. Wall *a* is provided with a shoulder *k* positioned so as to lie just outside of the edge of surface *j* when the latter is at the end of its stroke. 50 While it will be noted that surfaces *a* and *j*

are neither one exactly hemi-spherical, they should be so formed that they limit an explosion chamber which is, as nearly as practicable, of spherical form. The assembly is completed by a gasket *g* and bolts (not 55 shown) maintaining the cylinder head on block *e*.

In motors constructed according to the above description, the explosive mixture is forced in a whirl into a spherical chamber 60 which appears to favor a rapid propagation of the explosion wave and minimum cooling of the heated gases a sphere offering a minimum of cooling surface for any given volume. In practice, it is found, that higher compressions than the ordinary may be employed 65 without danger of auto-ignition.

The invention is not to be taken as limited to an explosion chamber of spherical form. Obviously, surfaces *a* and *j* may be made in 70 any concave form or only hemi-spherical in limited portions to obtain results superior to those of the cylinder head and piston of usual shape, the spherical explosion chamber representing a preferred form capable of yielding 75 a maximum of efficiency and power.

What I claim is:—

1. In combination, a cylinder, a cylinder head having a downwardly concave cavity therein mounted on said cylinder, a piston 80 slidably mounted in said cylinder and having on its upper face a sharply sloping ridge adjacent the inlet side of the cylinder and an upwardly concave surface having the center of the projection of the said surface on a horizontal plane offset from the center of the cylinder in the direction of the exhaust side of the cylinder, said ridge fitting closely the wall of said cavity when said piston is in its uppermost position, said cavity and said upwardly concave surface forming therebetween when said piston is in its uppermost 85 position a chamber, the width of said chamber being greater than half the width of said cylinder and said chamber being offset from the center of the cylinder towards the exhaust side thereof, and a spark plug positioned in said chamber.

2. In combination, a cylinder, a cylinder head having a downwardly concave cavity 100

therein mounted on said cylinder, a piston slidably mounted in said cylinder and having on its upper face a sharply sloping ridge adjacent the inlet side of the cylinder and an upwardly concave surface having the center of the projection of said surface on a horizontal plane offset from the center of the cylinder in the direction of the exhaust side of the cylinder, said ridge fitting closely the wall of said cavity when said piston is in its uppermost position, said cavity and said upwardly concave surface forming therebetween when said piston is in its uppermost position a chamber which extends from the exhaust side of the cylinder more than half the distance towards the inlet side thereof, and a spark plug positioned in said chamber.

3. In combination, a cylinder, a cylinder head having a downwardly concave cavity extending as far as the exhaust side of the cylinder mounted therein on said cylinder, a piston slidably mounted in said cylinder having on its upper face a sharply sloping ridge adjacent to but spaced from the inlet side of the cylinder adapted when the piston is in its uppermost position to fit closely the wall of said cavity, the remainder of the upper face of said piston being upwardly concave, whereby said cavity and said upwardly concave portion of the cylinder form when the cylinder is in its uppermost position a chamber whose one edge is formed by the meeting of the top of said ridge and the wall of said cavity and which extends from a point in the inlet half of said cylinder as far as the exhaust side of the cylinder, and a spark plug positioned in said chamber.

In testimony whereof I affix signature.

GUSTAVE EMILE CHÉDRU.
